UNITED STATES PATENT OFFICE.

HOWARD E. HARBAUGH, OF KENOSHA, WISCONSIN, ASSIGNOR TO THE BADGER BRASS MFG. CO., OF KENOSHA, WISCONSIN, A CORPORATION OF WISCONSIN.

SPRING-CATCH FOR LAMPS, &c.

No. 926,560.

Specification of Letters Patent.

Patented June 29, 1909.

Application filed September 24, 1908. Serial No. 454,506.

To all whom it may concern:

Be it known that I, HOWARD E. HARBAUGH, a citizen of the United States, residing at Kenosha, in the county of Kenosha and State of Wisconsin, have invented certain new and useful Improvements in Spring-Catches for Lamps, &c., of which the following is a specification.

This invention relates to spring catches for lamp doors and the like, and it has for its salient objects to provide a construction which may be formed wholly or substantially of spring wire, which will be extremely compact and of such configuration or shape that it will lie along the joint of connection between the two parts which are to be latched together without presenting prominent projections, especially when in closed or latched position; to provide a construction in which the latch members are under constant holding tension when closed, thus preventing rattling; to provide a construction in which the necessary flexing of the members of the latch in the opening and closing movements of the latter is distributed over a substantial length of wire, thus preventing the straining of the latter beyond its elastic limit; and in general, to provide a simple and improved mechanism of the character referred to.

The invention consists in the matters hereinafter described, and more particularly pointed out in the appended claims.

In the drawing, Figure 1 is a perspective view of a fragmentary portion of a headlight or lamp body equipped with a preferred embodiment of the invention; Fig. 2 is a view in horizontal section through the latch mechanism and the portions of the lamp body to which it is attached; the parts being shown on a scale larger than that of Fig. 1 and the latch mechanism being partly opened or in its intermediate position; Fig. 3 is a view generally similar to Fig. 2 showing the latch mechanism fully closed; Fig. 4 is a view taken approximately on line 4—4 of Fig. 3 and looking in the direction of the arrows. Fig. 5 is a detail of the catch member detached.

Referring to the drawings, mounted upon the door 1 to extend along the edge of the latter are two thimbles, as 2, 2, each of substantial length and of such internal diameter as to receive loosely the ends of a length of wire, designated as a whole 3. Said wire approximately fits the thimbles but is free to

rotate therein, and is held against endwise movement, conveniently by slightly riveting over the ends thereof at the remote ends of the thimbles, as indicated at 4. The wire is exposed for a considerable length of its central portion, and in this exposed portion is formed an integral elongated loop 5, the sides of which are brought together and into contact at the points where the loop joins the straight portions of the wire and surrounded by a collar 6, which is also shown as formed of wire simply bent into ring form. The main body of the loop is bent approximately at right angles to the contracted portion embraced by the collar 6; the bends, 70 designated 7 in the drawing, being approximately coincident with the portions of the loop which are deflected away from each other, thereby forming shoulders 8, 8, (see Fig. 4) located eccentrically of, or radially 75 remote from, the axis of the main length of the wire, *i. e.* the axis of the thimbles. For convenience of grasping, the extremity of the loop is turned outwardly, as indicated at 9.

The coöperating latch member, designated as a whole 10, consists preferably of a length of wire having two alined extensions 11 which extend along the margin of the body and are soldered or otherwise secured to the 80 interior of the latter, and an intermediate integral doubled portion forming a lug 12 which extends out through a suitable aperture in the body casing and has its outer end portion 13 bent approximately at right angles, as seen clearly in Fig. 3. The lug 12 extends somewhat obliquely outwardly from the body in such position that its bent end will pass through the inner end of the loop-latch 5 when the latter is oscillated on its 85 journals, and the inner face 14 of the extremity of this angular portion constitutes a strike portion which projects slightly into the path of movement of the strike portions or shoulders 8, 8, of the latter when said 90 journalled member is rotated on its pintles. The inner angle 15 of the hook-shaped catch is so shaped as to constitute in effect a recess which receives and holds the strike portion of the loop when the parts are in closed position; the parts being preferably under slight spring tension after being fully entered, so as to prevent rattling of the door.

The operation of the device is obvious from the foregoing, but it is to be noted that 110

the spring action, which is depended upon for permitting the parts to pass into and out of latched engagement, resides chiefly in the straight exposed parts of the pintle portions 5 3, although the catch-hook also doubtless yields slightly.

The catch is of peculiar adaptability to receptacles which have a door forming one side thereof, as for example the lamp body 10 shown, in which case the latch mechanism extends along the meeting edges of the body and door, and may not only be made to simulate the hinge at the opposite edge of the door but projects but little more than a 15 hinge when in latched position.

It will be understood from the foregoing description that the invention fully attains the several objects hereinbefore recited.

The invention may, of course, be somewhat modified to adapt it to various applications without in any sense departing from the spirit of the invention.

I claim as my invention:

1. In combination in a latch mechanism, 25 a movable member formed of resilient wire and comprising alined pintle-like journal portions, spaced apart journal supports therefor, a loop formed integrally with the intermediate portion of said movable member to 30 extend radially therefrom and having its side portions brought together to form at the radially inner end of the loop, a strike portion located eccentrically of the axis of rotation of the member, and an angular catch- 35 hook, the free end of which constitutes a strike portion, fixedly mounted with said strike portion projecting into the arc-shaped path of movement of the strike portion of the movable member and with its inner angle arranged to receive and hook over said 40 latter portion when in latched position.

2. In combination with a receptacle provided with a hinged door, a latch mechanism embodying a movable member formed of re-

silient wire and comprising alined pintle-like 45 journal portions, spaced apart journal thimbles mounted upon one member of the receptacle and receiving the extremities of said pintle-like journal portions, a loop formed integrally with the intermediate unsup- 50 ported portion of said movable member, arranged to extend radially therefrom and having its side portions deflected toward each other contiguous to their union with the pintle extensions to form at the radially 55 inner end of the loop, a strike portion located eccentrically of the axis of rotation of said member, means rigidly uniting the sides of said loop contiguous to the strike portion thereof, and an angular catch-hook fixedly 60 mounted upon the other member of said receptacle and arranged to project therefrom in position to pass through the loop when the door is in closed position, the angular extremity of said catch member being ar- 65 ranged to normally project into the oscillatory path of movement of the strike portion of the journaled member and being formed into hook-shape to hook over said latter strike portion when in closed position. 70

3. A latch mechanism comprising a movable member formed of resilient metal and provided with spaced-apart, alined journals and a catch-engaging projection between said journals, the strike portion of which is 75 radially remote from, or eccentric to, the axis of the member, a collar around said catch-engaging projection, and an angular catch hook, the strike portion of which is inclined to project into the arc-shaped path 80 of the strike portion of the movable member and the inner angle of which receives and hooks over said latter strike portion when in latched position.

HOWARD E. HARBAUGH.
